UNITED STATES PATENT OFFICE.

WILLIAM J. KINBACK, OF BETHLEHEM, PENNSYLVANIA.

WATER-MOTOR.

1,350,025.

Specification of Letters Patent. Patented Aug. 17, 1920.

Application filed October 5, 1917. Serial No. 194,895.

To all whom it may concern:

Be it known that I, WILLIAM J. KINBACK, a citizen of the United States, residing at Bethlehem, in the county of 5 Northampton and State of Pennsylvania, have invented certain new and useful Improvements in Water-Motors; and I do hereby declare the following to be a full, clear, and exact description of the invention, such 10 as will enable others skilled in the art to which it appertains to make and use the same.

This invention relates to water motors or water wheels, and the primary object of the 15 invention is to provide a water wheel which may be operated by a comparatively slow moving stream for transmitting power to any suitable type of mechanism, such as an electrical dynamo or the like.

Another object of this invention is to 20 provide a water wheel which comprises a pair of hub members having a plurality of sockets formed therein extending inwardly from their peripheries which receive the 25 spokes of the wheel, to the outer ends of which the paddles or blades are attached, and also to provide a plurality of links which connect the spokes short distances inwardly of the inner edges of the paddles or 30 blades for providing a light durable and strong water wheel.

With the foregoing and other objects in view this invention consists in such novel features of construction, combination and 35 arrangement of parts as will be hereinafter more fully described, illustrated in the accompanying drawings and claimed.

In describing the invention in detail reference will be had to the accompanying drawings 40 wherein like characters designate like and corresponding parts throughout the several views, and in which:

Figure 1 is a vertical section through the water wheel, and

Fig. 2 is a fragmentary side elevation of the wheel.

The wheel's support includes pillars 5, upon the upper ends of which are mounted suitable bearing supporting structures 6. A 50 shaft 10 is suitably journaled in the bearings 6.

The wheel structure comprises a pair of hub sections 14 and 15 which are held in connection with the shaft 10, for rotation 55 thereby by means of set screws 16. The hub sections 14 and 15 are provided with a plu-

rality of substantially frusto-triangularly shaped sockets 17 which extend inwardly from their peripheries, in spaced relation to each other as clearly shown in Fig. 2 of the drawings. The sockets 17 receive the inner ends of the spokes 18 of the wheel.

The spokes 18 radiate from the center of the hub sections 14 and 15 and they diverge, as they extend outwardly, as clearly shown in Fig. 2 of the drawings. The spokes 18 have paddles or blades 19 attached to their outer ends. The spokes carried by the hub sections 14 are disposed directly opposite to the spokes carried by the hub sections 15, so that one spoke which is carried by the hub 14 will coat with the corresponding spoke carried by the hub 15 for forming a pair of spokes to which one of the paddles or blades 19 is attached.

The paddles or blades 19 are constructed of angled metal or of wood if desired, having relatively long sides 20 and short sides 21 which are disposed at right angles to the long sides 20, as clearly shown in Fig. 2 of the drawings. The blades 19 are disposed so that the angled sides 21 in connection with the sides 20 will form a sort of cup, for receiving the water and increasing the efficiency of the wheel 12.

The shaft 10 has a pulley or power transmitting wheel 22 mounted thereon, which may be connected by a belt or suitable transmission to any suitable type of mechanism.

If it is so desired, a battery of the wheels 90 may be provided and all of them connected by suitable power transmitting means to a single machine or series of machines as desired.

The spokes 18 are connected one to the other by brace bars 25, as shown at 26. The braces 25 are positioned short distances inwardly from the inner edges of the blades 19.

From the foregoing description taken in connection with the accompanying drawings 100 the advantages of construction and the method of operation of the improved water motor, will be readily apparent to those skilled in the art to which this invention appertains and, while in the foregoing description, the principle of the operation of this invention has been described together with various features of construction, it is to be understood that certain minor features of construction, combination and arrangement 110 of parts may be altered to suit practical conditions provided such alterations are com-

2
prehended within the scope of what is claimed.

What is claimed is:—

- A water motor comprising a shaft, a hub
5 mounted upon the shaft and provided at its periphery with radially disposed sockets, radially disposed spokes having their inner ends secured in the sockets of the hub, blades carried at the outer end of the spokes, and
10 links secured at their ends to the adjacent spokes and bridging the space between them and holding the spokes in radial position with relation to the shaft, the end portions

of the adjacent links overlapping each other and the links being arranged substantially 15 in an arcuate line around the center of the shaft, each arcuate line lying against one side of the spokes and the other side lying against the opposite sides of the spokes.

In testimony whereof I affix my signature 20 in presence of two witnesses.

WILLIAM J. KINBACK. [L.S.]
